UNITED STATES PATENT OFFICE.

JOSEPH DICK, OF CANTON, OHIO.

FODDER-CUTTER.

SPECIFICATION forming part of Letters Patent No. 613,668, dated November 8, 1898.

Application filed April 8, 1897. Serial No. 631,285. (No model.)

To all whom it may concern:

Be it known that I, JOSEPH DICK, a citizen of the United States, and a resident of the city of Canton, county of Stark, State of Ohio, 5 have invented a new and useful Improvement in Fodder-Cutters, of which the following is a full, clear, and exact description, reference being had to the accompanying drawings, making part of this specification.

10 My invention relates to fodder cutters and shredders; and its object is to provide an improved construction of the same which shall possess superior advantages with respect to efficiency and use.

15 The invention consists in a novel construction and combination of parts hereinafter fully described and claimed.

In the accompanying drawings, Figure 1 is a perspective view of a fodder-cutter constructed in accordance with my invention, the upper portion of the fan-casing being removed to show the knives and fan-blades in their relation to the fan-wheel. Fig. 2 is a rear view of the machine, showing the fan-casing 25 and its method of attachment to the frame.

Fig. 3 is a sectional view through the fan-casing, showing the driving-shaft and the fly-wheel mounted thereon. Fig. 4 is a view of the leg extension. Fig. 5 is a sectional view 30 of the leg extension. Fig. 6 is a plan view of the fan-wheel, showing the rotating cutter and fan-blades. Fig. 7 is a perspective view of the double cam-faced adjusting device.

Fig. 7^a is a similar view of a single cam-faced 35 adjusting device. Fig. 8 is a perspective view of the rotating-cutter extension. Fig. 9 is a sectional view of the rotating cutters and the extension thereof and showing the manner of attaching the same to the fly-wheel. Fig.

40 Fig. 10 is a sectional view of the shredder and the shredder-plate and the manner of adjusting the same to the fly-wheel. Fig. 11 is an enlarged fragmentary view of the fly-wheel and fan, and Fig. 12 is an end view of the same.

45 A is a solid fly-wheel adapted to be mounted upon a shaft and journaled in any of the well-known forms of fodder-cutter frames and to be driven by a belt-pulley mounted upon the outer end of the shaft. Upon the rim of this fly-wheel 50 there are provided a series of fans B, which fit over the edge thereof and upon either side

thereof and have a brace b, engaging with the upper and outer end thereof and with holes arranged in the fly-wheel, by means of which the fans are capable of adjustment at different angles. Around the hub upon which the fly-wheel A is mounted and upon either side of the fly-wheel are arranged a series of fan-blades b', which force the material away from the center of the fly-wheel and prevent it from engaging with or choking the shaft. Through the fly-wheel there are bored a series of holes at such places as may be desired for the purpose of attaching to the fly-wheel by means of bolts or otherwise rotating cutters. I prefer to use and have shown the rotating cutters C and the rotating shredder-knives D arranged to be adjusted in their relation to the cutter-plate and the feed-box by means of adjusting-plates E, having the 70 upper face thereof provided with segmental cam-racks e and either a double or single cam-face e' to engage with corresponding segmental cam-racks e² and cam-faces e³, arranged upon the under portion of the knife 75 extension F. The knife extension F is provided with a brace e⁴, cast integral therewith, which connects the upper portion of the knife extension with the horizontal extension carrying the segmental rack e². Upon the fly-wheel there is provided a lug e⁵, which passes between the lugs e⁶ and e⁷, cast upon the under side of the horizontal extension of the knife extension F and prevents the rotary movement thereof. When it is desired to 85 adjust the knives either forward or backward, the screw-bolt passing through the knife and fly-wheel is partially unscrewed, when the segmental rack may be moved forward or backward, raising or lowering the extension 90 and rotating cutters or plates carrying the shredders, and may again be screwed down or locked in the desired adjustment. The fly-wheel thus provided may be mounted in any of the well-known forms of fodder-cutter 95 frames and driven either by hand or steam power; but I prefer to and have shown it mounted upon a shaft and journaled in a frame, with a belt-pulley upon the outer end of the shaft. To the inner journal-box I attach a sleeve G, which extends to the hub of the fly-wheel, forming a shield or covering 100

which prevents the cut material from winding around or binding upon the revolving driving-shaft. Around the fly-wheel thus mounted and carrying the rotating cutting-knives or shredder-knives I provide the fan-casing H, with the air-inlets h arranged around the driving-shaft at the center of the fan-casing. I also provide a door or opening h' at the bottom of the fan-casing, so that in case any portion of the machinery should become loosened and drop down into the fan-casing it could be readily removed.

For the purpose of adjusting the frame of the machine so that the cutters will run even and without vibration and to adapt the legs of the frame to any inequality in the floor or surface upon which the machine may be stationed I provide a leg extension M, which consists of a piece of cast metal having a slot m therein and a lug m' upon its outer surface. Through the slot m there is passed a bolt which engages with the leg of the frame and carries a cam-piece m². When it is desired to raise or lower the frame, the nut on the bolt is released and the cam-piece m² is moved around so as to raise or lower the leg extension to the desired position, when, the nut being turned fast upon the bolt, the parts are securely locked together and to the leg.

That the material to be cut or shredded may be evenly and continuously fed to the machine without the ordinary hand pressure or manipulation I have provided a continuous feed-table N.

Having thus fully described my invention, what I desire to claim and secure by Letters Patent is—

1. In a fodder-cutter, the combination with a solid fly-wheel having mounted thereon a series of adjustable cutters or shredders, the adjustable fan-blades secured to the periphery of said fly-wheel, extension-posts engaging the cutters and fly-wheel, the adjustable plates having cast therewith segmental cam-racks and one or more cam-faces, and the

connecting screw-bolts, substantially as described.

2. In a fodder-cutter, the combination with the fly-wheel, having mounted thereon a series of adjustable cutters or shredders, the fan-blades secured to the circumference or periphery of said fly-wheel, the fan-blades attached to the hub of the fly-wheel, and the fan-casing provided with an air inlet and exhaust pipe, substantially as described. 55

3. In a fodder-cutter, the combination with the fly-wheel having mounted thereon a series of adjustable cutters or shredders, the adjustable fan-blades secured to the periphery of said fly-wheel, the fan-blades secured to the hub of the fly-wheel, the extension-posts engaging the cutters and fly-wheel, the adjustable plates having cast therewith segmental cam-racks and one or more cam-faces, and the connecting screw-bolts, substantially 60 as described. 65

4. The combination in a fodder-cutter, of a knife-extension brace, adapted to be held in engagement with the fly-wheel, adjusting-plates engaging therewith having cast thereon segmental cam-racks and one or more cam-faces, adapted to engage with corresponding cam racks and faces on the extension-post, substantially as described and for the purpose set forth. 70

5. The combination in a fodder-cutter, and with the leg of the supporting-frame thereof, of a sliding plate and a cam-plate adapted to engage with the lug on the sliding extension-plate, and means for locking them in engagement with each other, and with the leg, substantially as described and for the purpose set forth. 75

In testimony whereof I have hereunto set my hand this 30th day of March, A. D. 1897. 80

JOSEPH DICK.
